UNITED STATES PATENT OFFICE.

CHARLES L. HOPKINS, OF ALLEMANDS, LOUISIANA.

FLOOR-SET.

No. 822,126.

Specification of Letters Patent.

Patented May 29, 1906.

Application filed January 12, 1905. Serial No. 240,828.

To all whom it may concern:

Be it known that I, CHARLES L. HOPKINS, a citizen of the United States, residing at Allemans, in the parish of St. Charles and State of Louisiana, have invented certain new and useful Improvements in Floor-Sets, of which the following is a specification.

My invention relates to floor-sets; and its object is to provide a simple, compact, and durable device of this character which can be readily applied to a floor-joist and by the use of which the boards of a floor can be quickly forced together and held during the operation of securing them in position.

15 The object of the invention is also to provide means for securely fastening the device in position.

With the above and other objects in view the invention consists of a box preferably 20 formed of a blank of sheet metal and provided with depending portions for overlapping the joist of a floor. These depending portions are provided with securing devices for clamping upon the joist and securing the floor-set 25 in position thereon. One end of the box is preferably beveled and is adapted to be contacted by a wedge which is inserted between the box and the board to be clamped in position.

30 The invention also consists in the further novel constructions and combinations of parts hereinafter more fully described and claimed.

In the accompanying drawings I have 35 shown the preferred forms of my invention.

In said drawings, Figure 1 is a perspective view of the floor-set applied to a joist and showing a wedge interposed between it and the boards of the floor. Fig. 2 is a front perspective view of the floor-set detached. Fig. 3 is a detail view of a blank from which the set may be formed, and Fig. 4 is a top plan view of a modified form of floor-set.

Referring to the figures by numerals of reference, 1 is a top plate having parallel side flanges 2 depending therefrom and integral therewith. An end supporting-flange 3 is formed at one end of the plate 1 and is interposed between the ends of the flanges 2. At 45 the opposite end of the plate 1 is formed a head 4, which overlaps the adjoining ends of flanges 2 and has integral wings which extend laterally from the head, as shown at 5. Head 4 forms a support for the top plate and 50 extends downward therefrom a distance equal to the height of the end flange 3. The

wings 5, however, are greater in height than the head, so that a broad surface is presented to the wedge used in connection with the device and which will be hereinafter described. 60 Head 4 and its wings 5 are also preferably formed at an incline or bevel to the side flanges 2 for the purpose hereinafter more fully described. Apertures 6 are provided in each side flange, and these are screw-threaded and receive set-screws 7, having heads 8 of such a form as to permit them to be readily turned manually. All of these screws are located in a plane below the head 4 and flange 3. 70

In using the floor-set herein described the same is placed on a joist 9, with the flanges 2 overlapping the sides thereof, and with the head 4 and flange 3 bearing thereupon. The set-screws 7 are then forced into engagement 75 with the joist and will hold the floor-set against movement. A desired number of boards 10 are then placed in proper position on the joists and a wedge 11 inserted between them and the head 4 and wings 5. This 80 wedge is subsequently driven against the inclined head 4 and wings 5 and will, as is obvious, force the boards tightly together and hold them in place. They can then be nailed or otherwise permanently fastened, and the 85 floor-set can then be readjusted for use with another set of boards.

In Fig. 4 I have shown a modified form of floor-set in which a cam 12 is employed in lieu of the set-screws 7 hereinbefore referred to. 90 By swinging the cam in one direction it will firmly bind upon a joist, and any backward pressure upon the device will tend to more firmly secure the same in place. With this arrangement the floor-set can be more 95 quickly placed in position than where a multiplicity of securing devices are employed.

By referring to Fig. 3 it will be seen that each floor-set can be readily struck from a blank of sheet metal. It is obvious, therefore, that they can be constructed at slight cost and at the same time be rendered very durable and compact. 100

In the foregoing description I have shown the preferred form of my invention; but I do 105 not limit myself thereto, as I am aware that modifications may be made therein without departing from the spirit or sacrificing the advantages thereof, and I therefore reserve the right to make such changes as fairly fall 110 within the scope of my invention.

Having thus fully described my invention,

what I therefore claim as new, and desire to secure by Letters Patent, is—

1. A floor-set consisting of a body comprising connected side portions and clamping means on one of said portions, and an inclined head at one end of the body, and wings extending laterally from the head.

2. A floor-set consisting of a body comprising connected side portions and a securing device on one of said portions, and a head connected to the body, and wings extending laterally therefrom.

3. A floor-set consisting of a body comprising connected side portions, a securing device on one of said portions, and a supporting-flange at one end of the body, and a supporting-head at the other end of the body, and wings extending therefrom.

4. A floor-set consisting of a body comprising

connected side portions, a securing device on one of said portions, and a supporting-flange at one end of the body, and an inclined supporting-head at the other end of the body, and alining wings extending laterally from the head.

5. A floor-set formed in a single sheet of metal and comprising a top plate, side flanges, an end supporting-flange, a head at the other end of the top plate and overlapping the ends of the side flanges, and wings integral with the head.

In testimony whereof I affix my signature in presence of two witnesses.

CHARLES L. HOPKINS.
